RELISH DISH OR SIMILAR ARTICLE

Ernest T. Simondetti, Florence, Italy, assignor to Fisher Bruce & Company, Philadelphia, Pa., a corporation of Pennsylvania

Application January 31, 1956, Serial No. 39,977

Term of patent 7 years

(Cl. D44—15)

Figure 1 is a top plan view of a relish dish or similar article showing my new design;

I claim:

The ornamental design for relish dish or similar article, as shown.
